UNITED STATES PATENT OFFICE.

LE ROY C. SCHENCK, OF EAST MOLINE, ILLINOIS, ASSIGNOR TO TROY LAUNDRY MACHINERY CO., LTD., OF EAST MOLINE, ILLINOIS, A CORPORATION OF NEW YORK.

SAFETY SWITCH FOR CENTRIFUGAL MACHINES.

Application filed January 7, 1927. Serial No. 159,567.

The present invention relates to safety switches for centrifugal machines.

The present invention is particularly useful and will be described in connection with centrifugal extractors such as are used for extracting moisture from washed clothes. In a well known type of extractor a basket adapted to receive the washed clothes is suspended from above and given a movement of rotation. In the event that the basket is unevenly loaded, undesirable gyrations may be set up in the basket. It has been customary for the operator to watch his extractor for a short time after loading the machine and setting same in operation, to make sure that the load was not too greatly out of balance. In case the operator should find that the load was too greatly out of balance, he would stop the machine before it reached full speed and would distribute the goods more evenly. There have been instances, however, when the operator would load the basket, start the motor for driving said basket and walk away. If the basket were badly loaded, considerable damage to the machine might result.

An object of the present invention is to provide a safety switch for a centrifugal machine which switch will result in the de- energization of the driving motor in case gyrations of more than a predetermined amplitude are set up.

A further object is to provide a simple switch which may be readily attached to centrifugal extractors as now commonly known and used.

A further object is to provide a switch which is sturdy, not likely to get out of order, and which may be manufactured at a relatively small cost.

Referring to the drawings—

Figure 1 is a sectional view of the upper portion of a centrifugal extractor showing one embodiment of the present invention applied thereto;

Figure 2 is a detail view on an enlarged scale showing a portion of the switch mechanism, said view being taken along the plane indicated by the arrows 2—2 of Figure 1; and

Figure 3 is a view taken along the same plane as Figure 2 but looking in the opposite direction.

The numeral 1 indicates the rotatable shaft of a centrifugal machine which shaft

may have supported at the lower extremity thereof a basket of goods which are to be whirled to extract moisture therefrom. Said shaft is provided near its upper extremity with a bushing 2 having a portion 3 presenting a spherical surface constituting part of a universal joint. The spherical portion 3 is housed within a spherical bearing provided by the top casting 4 and the bottom casting 5, said top casting 4, in the illustrated embodiment of the present invention, comprising a rigid portion of an extractor. The bottom casting 5 is resiliently supported on the top casting 4 by means of the bolts 6—6, spring 7—7 being provided between the nuts on said bolts 6—6 and abutting portions of the casting 4 to permit relative movement between the casting 5 and the casting 4. By reason of this construction, adjustment is automatically made as wear occurs.

Keyed to the upper extremity of the shaft 1 is the cup-shaped member 8, which constitutes one member of a mechanical clutch, the cooperating member of which is indicated by the numeral 9. The numerals 10—10 indicate blocks housed within the clutch member 8, which blocks under the effects of centrifugal force are adapted to fly outwardly against the inner wall of said clutch member 8 to have gripping engagement therewith. The clutch member 9 is adapted to be driven by any suitable source of power, an electric motor being preferred. The details of the clutch, comprising the members 8, 9 and 10, need not be described in detail, inasmuch as clutches suitable for the purpose will occur to those skilled in the art. It may be said, however, that when the clutch member 9 is driven at or above a predetermined speed, the blocks 10 will fly outwardly into gripping relationship with the clutch member 8, whereby to communicate a driving movement to said clutch member 8. Inasmuch as said clutch member 8 is keyed to the shaft 1, a turning movement will be communicated to said shaft 1. The shaft 1 carries at or near its lower extremity a basket (not shown) for holding the goods from which moisture is to be extracted. A very serious problem in the operation of centrifugal extractors arises from unbalanced loads. The present invention contemplates a structure whereby the shaft 1 will be prevented from rotating at danger-

ous speeds in case undesirable gyrations should be set up.

Mounted upon the outside of the casting 4 is a switch box indicated by the numeral 11, 5 said switch box being secured to said casting 4 by any preferred holding means, a screw 12 being illustrated for that purpose.

The switch box 11 comprises a housing 13, which provides bearings for a rotatable shaft 14. Secured to said shaft 14 is the arm 15, which has pivotally secured thereto the pair of switch contact members 16—16, which are 10 electrically connected together. Mounted upon the housing 13 is a cover plate 17, 15 which may be made of insulating material and which provides a support for a pair of relatively stationary switch contact members 18—18. A spring 19 is provided, which in the illustrated embodiment of the present 20 invention is a coil spring disposed upon the shaft 14. Said spring has one of its terminals in abutting relationship with the housing 13 and the other of its terminals in 25 abutting relationship with the arm 15. Said 30 spring normally holds the switch members 16—16 in contacting relationship with the relatively stationary contact members 18—18. Keyed to the shaft 14 is a lever 20, which lever has its end portion extending through 35 an aperture 21 in the casting 1 into proximity with the clutch member 8.

The relatively stationary contact members 18—18 will be connected in the electrical circuit of the motor for driving the 35 clutch member 9, whereby when the electrical connection between said contact members 18—18 is broken, the electrical circuit of the driving motor will be interrupted. As noted above, the spring 19 normally 40 holds the contact members 16—16 in contacting relationship with the members 18—18. Inasmuch as said contact members 16—16 are connected together, an electrical connection is normally provided between the 45 contact members 18—18. In case undesirable gyrations should be set up in the shaft 1, the clutch member 8 will be moved out 50 of the symmetrical position in which it is illustrated in Figure 1, into contacting relationship with the lever 20. This movement will result in movement of the lever 20, which in turn results in disengagement of 55 contact members 16—16 from the contact members 18—18, breaking the electric circuit of the driving motor.

According to the illustrated embodiment of the present invention, interruption of the electric circuit of the driving motor will be only temporary, the spring 19 automatically 60 moving the contact members 16—16 into contact making position when the clutch member 8 is again at or near its symmetrical position. The net effect is, however, that it 65 will be impossible for the clutch member and shaft 1 to acquire a velocity such as will pro-

duce the undesirable gyrations referred to. It will be understood, of course, that, if preferred, the switch mechanism 11 may be of the snap variety, whereby when once the lever 20 has been moved outwardly by the 70 clutch member 8, the contact members 16—16 will be held out of engaging relationship with the contact members 18—18 until the operator has given attention to the machine and taken some positive steps to bring the 75 contact members 16—16 into engaging relationship with the contact members 18—18.

Though the illustrated embodiment of the present invention shows the lever 20 to be in position to be operated by the clutch member 8, it will be understood that said lever 20 may be located in position to be operated by any other part of the machine which is subject to undesirable gyrations. Many other modifications will occur to those 85 skilled in the art. It is intended to cover all such modifications that fall within the scope of the appended claims.

What is claimed is—

1. In a centrifugal machine, in combination, a relatively fixed housing, a rotary member within said housing, and an electric switch carried by said housing for controlling the rotation of said rotary member, said switch having means adapted to be engaged by said rotary member to open said switch when said rotary member acquires undesirable gyrations. 90

2. In a centrifugal machine, in combination, a relatively fixed housing, a rotary member within said housing, and an electric switch for controlling the rotation of said rotary member, said switch having means adapted to be engaged by said rotary member to open said switch when said rotary member acquires undesirable gyrations, said switch being mounted upon the outside of said housing and having said means extending through the wall of said housing to the interior thereof into proximity to said rotary member. 100

3. In a centrifugal extractor, in combination, a rotary shaft, supporting means for said shaft permitting a universal movement thereof, a clutch member secured to said shaft, a complementary clutch member for communicating the movement to said first mentioned clutch member, an electric switch for controlling the rotation of said complementary clutch member, said switch having means adapted to be engaged by said first mentioned clutch member to open said switch when said first mentioned clutch member acquires undesirable gyrations. 115

4. In combination, a relatively fixed housing, a rotary shaft supported thereby being capable of universal movement relative thereto, a clutch member secured to said shaft, a complementary clutch member adapted to communicate rotary movement to 120 125 130

said first mentioned clutch member, a switch for controlling the movement of said complementary clutch member, said switch being mounted upon the outside of said housing and 5 having means extending through the wall of said housing into proximity to said first mentioned clutch member in position to be engaged by said first mentioned clutch member when gyrations of predetermined amplitude 10 tude are set up.

5. In a centrifugal machine, in combination, a rotary shaft subject to gyrations, an electric switch for controlling the rotation of said shaft, said switch having means adapted to be engaged by said shaft when 15 gyrations of predetermined amplitude are set up.

Signed at East Moline, Illinois, this 3rd day of January, 1927.

LE ROY C. SCHENCK.
